Fig. 1

Fig. 1 is a front perspective view of a concrete batch plant showing my new design; and

Fig. 2 is a rear view thereof.

The opposite side is similar in appearance to the side shown in Fig. 1.

The design for the concrete batch plant disclosed is characterized by the conveyor support comprising the ground-engaging standard and the top bracket unit as shown.

I claim:

The ornamental design for a concrete batch plant, as shown and described.
